UNITED STATES PATENT OFFICE.

DENNIS M. LONG AND JOHN KILLER, OF LOUISVILLE, KENTUCKY.

PIPE-MOLDING PIT.

SPECIFICATION forming part of Letters Patent No. 293,480, dated February 12, 1884.

Application filed November 30, 1883. (No model.)

To all whom it may concern:

Be it known that we, DENNIS M. LONG and JOHN KILLER, of Louisville, Kentucky, have invented a new and useful Improvement in 5 Pipe-Molding Pits, of which the following is a specification.

Our invention relates to such molding or ramming pits as are used in the manufacture of cast-iron pipes; and it consists, generally, 10 of the combination of a wall-plate and its attachments; and the object is to hold a double flask for casting iron pipe in position while being rammed, and to prevent it from being raised from the bottom of the pit when the 15 patterns are being drawn up out of the molds.

In the accompanying drawings, Figure 1 is an elevation, and Fig. 2 a plan, of our improvement, the same letters representing like parts in each.

20 A is the swinging bar, preferably of wrought-iron.

B are lugs cast on and forming part of the wall-plate E.

C is a bolt or pin securing the swinging bar A.

D is the ramming-pit wall.

E is a wall-plate built in and secured to the pit-wall D.

F is a double flask.

30 G is a projecting rib on the flask F.

H is a clamp for securing the chill-plate J to the flask F.

I is a wedge for securing and holding the clamp H in position.

35 J is a chill-plate.

It has been found, in practice, in the use of double flasks, and in drawing the two patterns from the molds at once, that the patterns, instead of themselves drawing, raise the flask

up from the bottom of the pit. Our improvement overcomes this difficulty, holds the flask securely in position, and facilitates the drawing of the patterns.

Our improvement consists, more particularly, 45 of the wall-plate E, built in and secured to the pit-wall D, furnished with the lugs B and carrying the swinging bars A, attached between the lugs to the plate by means of the bolt or pin C.

In practice, the bars A, previously to the 50 reception into the pit of a flask to be rammed, are swung back into the position occupied by the right-hand bar in Fig. 2, and the flask is lowered into the pit, set on, and secured to chill-plate J by the clamp H and wedge I. 55 The bars A are then swung forward and left projecting over the rib G of the flask, as shown in Fig. 1, and by the left-hand bar in Fig. 2, after which the flask is rammed, the patterns drawn, and the bars A again swung back from 60 over and clear of the rib G, so as to allow the flask to be swung from the ramming-pit to the oven, thus preparing the ramming-pit for the 65 reception of another flask.

We do not wish to be understood as limiting our invention to a use with double flasks simply, as it is equally adapted to be used with triple and other multiple flasks.

Having fully described our invention, what we claim as new, and desire to secure by Letters Patent, is—

The combination of the wall D, the plate E, and the bars A, substantially as described.

DENNIS M. LONG.

JOHN KILLER.
